SUPERIMPOSED DUPLEX LOUD-SPEAKER

John F. Marquis, Haddonfield, N. J., assignor to
 Radio Corporation of America, a corporation
 of Delaware

Application May 30, 1942, Serial No. 445,179

1 Claim. (Cl. 179—109)

1

This invention relates to signal translating apparatus, and more particularly to a loudspeaker having an extended range of reproduction.

Various loudspeaker constructions have been proposed heretofore wherein two or more diaphragms are provided, each with its own driving motor, and each adapted to reproduce most efficiently over a particular band of frequencies within the acoustic range. Among the suggestions of this type proposed heretofore is that involving the use of a dynamically driven diaphragm for reproducing the lower frequencies, and a second diaphragm driven by a piezoelectric driver for reproducing the higher frequencies. An example of such a loudspeaker is shown in the Harris Patent No. 1,932,459, granted October 31, 1933. However, loudspeakers of this type, as heretofore constructed, have the disadvantage that the coupling member between the piezoelectric driver and its diaphragm has a fair amount of compliance, and this cuts down the high frequency response. The additional mass introduced into the vibrating system by the aforesaid coupling member also reduces the high frequency response, so that full advantage cannot be taken of the high frequency range over which the piezoelectric driver is adapted to operate.

The primary object of my present invention is to provide an improved loudspeaker having an extended range of reproduction and which is free from the aforementioned defects.

More particularly, it is an object of my present invention to provide an improved loudspeaker construction embodying a low frequency unit and a high frequency unit, the latter of which is adapted to operate efficiently over a wide range.

Another object of my present invention is to provide an improved loudspeaker as aforesaid in which the moving parts have a minimum mass.

Still another object of my invention is to provide an improved loudspeaker of the type set forth which is characterized by a minimum number of mechanical parts, thereby reducing the cost and greatly facilitating the assembly thereof.

It is also an object of my present invention to provide an improved loudspeaker as above described which is highly efficient in use and which will have a long life under ordinary conditions of use.

In accordance with my invention, I provide a unitary loudspeaker construction which comprises a relatively large diaphragm, preferably of the cone type, driven by a suitable electro-mechanical converter, such as a dynamic or other suitable magnetic driver or motor which operates

2

efficiently at the lower acoustic frequencies, and mount a piezoelectric element within the cone in proximity to its apex end. The piezoelectric element, constituting a second electromechanical converter, is connected to the cone at a plurality of spaced points around its own periphery, with at least one point on its periphery free from contact with the cone, whereby the last mentioned peripheral point of the element is free to vibrate.

According to one modification of my invention, a second, smaller cone diaphragm has its apex end connected directly to the aforementioned free, peripheral point of the piezoelectric element without any intervening coupling devices, the piezoelectric element serving as a motor to drive the small cone alone at the higher frequencies.

The smaller diaphragm is also nested within, preferably concentrically with, the larger diaphragm and may have its periphery or mouth either freely suspended or connected to the body of the large diaphragm by a suitable compliant coupling, as may be found most desirable.

In accordance with another modification of my present invention, the piezoelectric element may have an area sufficiently large to radiate or generate acoustic waves directly upon being energized to vibrate at acoustic frequencies. In either case, the mass of the moving, high frequency system is extremely small and does not appreciably

cut down the high frequency response. Also, the absence of a compliant coupling between the piezoelectric driver and its associated small diaphragm aids greatly in obtaining response over an extended high frequency range. The crystal driver and the dynamic driver may be connected to the same source of audio A.-C. power and so adjusted as to increase the sound output of the unit at frequencies above the normal cut-off frequency of the dynamic portion of the unit alone.

40 The novel features that I consider characteristic of my invention are set forth with particularity in the appended claims. The invention itself, however, both as to its organization and method of operation, as well as additional objects and advantages thereof, will best be understood from the following description of two embodiments thereof, when read in connection with the accompanying drawing, in which

Figure 1 is a central sectional view of one form 50 of loudspeaker constructed in accordance with this invention,

Figure 2 is a fragmentary, plan view thereof,

Figure 3 is a fragmentary, detail, sectional view showing one manner of attaching the piezoelectric element to the large cone,

Figure 4 is a view similar to Fig. 1 but showing another form of my invention, and

Figure 5 is a fragmentary, plan view of the latter form of my invention.

Referring more particularly to the drawing, wherein similar reference characters designate corresponding parts throughout, there is shown, in Figs. 1, 2 and 3, a relatively large, cone type diaphragm 1 suitably supported at its mouth or periphery by a pair of rings 3 and having a voice coil form 5 on which is wound a voice coil 7. The voice coil 7 may be suitably centered by a spider 9 in the angular air gap of a suitable magnetic or electromagnetic structure 11, all as is well known in the prior art. The voice coil 7 may be fed from a suitable audio frequency source through a circuit which includes a coupling transformer 13 and which may be designed to deliver to the voice coil 7 low frequency energy for which the relatively large cone 1 is particularly suited.

Supported entirely on and nested within the cone diaphragm 1 in proximity to its apex end is a piezoelectric element 15 of any suitable type, such as a Rochelle salt crystal or the like. The crystal 15 is preferably polygonal in shape (for example, of square shape) and has all but one of its corners clamped between and preferably cemented to a pair of tabs or the like 17 projecting from a clip or similar holding device 19, the base of which is cemented to the large diaphragm 1 in proximity to its apex end, as most clearly shown in Fig. 3. The piezoelectric crystal element 15 is so disposed on the diaphragm 1 in the modification of Figs. 1 to 3 that its free corner 15a is substantially on the axis of the cone 1. A small cone diaphragm 21, which has a mouth or base diameter considerably smaller than the mouth diameter of the cone 1 and is particularly suited for operation at the higher frequencies, has its apex cemented or otherwise suitably secured directly to the free corner 15a of the crystal 15 without any intervening coupling element which would normally introduce more or less compliance therebetween. The cone 21 is preferably much smaller than the diaphragm 1 and its mouth or periphery may either be freely suspended, or a compliant ring, or the like 23 may connect the mouth of the small diaphragm 21 to the body of the large diaphragm 1, if desired. The crystal 15 may be connected to the same audio frequency source as the voice coil 7, as clearly shown in Fig. 1, by a suitable circuit which may include a capacitor 25 which will pass the higher frequencies but filter out the lower frequencies as well as any direct current. At the lower frequencies, the cone 1, its voice coil 7, the crystal 15 and its diaphragm 21 all move together as a unit. At the higher frequencies, however, the cone 1 is practically stationary and only the crystal 15 and its cone 21 move.

The modification of my invention shown in Figs. 4 and 5 is quite similar to that heretofore described. However, instead of providing the small diaphragm 21, the crystal or other piezoelectric element 15 may be made sufficiently large so that it will have a vibrating surface which is capable of generating acoustical waves when the

crystal or the like is vibrated at acoustic frequencies. In this case, the piezoelectric element 15 is preferably made considerably larger than the corresponding element of Figs. 1 to 3, and it is mounted on the diaphragm 1 in the manner heretofore described with one of its corners 15a or some other suitable point or points on its periphery slightly spaced from the cone 1, whereby the latter point or points are freely suspended. As shown in Figs. 4 and 5, this form of crystal is preferably mounted so that it is concentric with the cone 1. Here, again, the element 15 vibrates bodily as a unit with the large cone 1 at the lower frequencies, while at the higher frequencies, practically all motion is in the element 15 which now vibrates relative to the cone 1.

From the foregoing description, it will be apparent to those skilled in the art that I have provided a novel loudspeaker construction comprised of a minimum number of parts and capable of reproducing acoustic frequencies over a wide and extended range. Although I have shown and described but two embodiments of my invention, it will be apparent to those skilled in the art that many other modifications thereof are possible. It will also be apparent, no doubt, that the construction herein described may also be used as a pick-up device or microphone, as well as a loudspeaker. I therefore desire that my invention shall not be limited except insofar as is made necessary by the prior art and by the spirit of the appended claim.

I claim as my invention:

A loudspeaker comprising a pair of conical diaphragms, a magnetic motor including a movable element connected to a first one of said diaphragms for driving said first diaphragm, and a piezoelectric motor carried by said first diaphragm, the other of said diaphragms being connected to said piezoelectric motor and being adapted to be driven by said piezoelectric motor, said other diaphragm and said piezoelectric motor being nested within said first diaphragm, said other diaphragm having a mouth diameter which is smaller than that of said first diaphragm, and the mouth of said other diaphragm having a compliant connection with said first diaphragm.
